WINDOW CORNICE

Robert W. Hyde, Cincinnati, Ohio, assignor to
 The Clopay Corporation, Cincinnati, Ohio, a
 corporation of Maryland

Application January 11, 1949, Serial No. 70,357

5 Claims. (Cl. 160—38)

1

This invention relates to window drapes or curtains and is particularly directed to an improved valance or cornice arranged to be mounted at the top of a window frame to suspend the drapes and to impart an attractive, trim appearance to the installation.

Window drapes or curtains customarily are suspended from drapery fixtures such as curtain rods fixed to the top of the window frame. A valance usually is extended across the top to enhance the appearance of the draperies and to conceal from view the shade, brackets and other hardware with which most windows are equipped. Ordinarily the valance consists of a ruffled fabric strip draped directly upon the curtain rod as a continuation of the drapes or it may be supported by a separate rod mounted in front of the curtain rod and arranged to overhang the upper portion of the drapes. In other instances, a cornice, formed of an appropriately decorated self-supporting panel such as plywood, may be installed instead of the fabric valance. A cornice of this construction is rather costly and difficult to fit and install by the householder, and therefore is used rarely in the home.

The present cornice structure is designed primarily for installation with fibre or paper drapes, although it may be used also with fabric drapes and curtains. These drapes are fabricated from a rather light weight drapery paper, printed in attractive patterns and colors and often creped or embossed to provide a cloth-like texture. They are relatively inexpensive, although in appearance they closely resemble the more costly fabric drapes. By reason of their low cost they may be discarded when soiled and replaced with new ones.

A primary object of the invention has been to provide an inexpensive cornice for use with drapes or curtains, either of cloth or paper, so that the cornice and drapes may be furnished in matching or complementary sets to be conveniently installed by the householder.

It is the concept of the invention to provide a cornice fabricated of sheet material such as fibre or plastic, doubled upon itself with its sides balloonized outwardly to form a semi-elliptical tube providing maximum strength and rigidity, printed or covered with a drapery material which carries out or blends with the drapery design and which provides a sturdy support from which the drapes may be suspended. Although fabricated from sheet material such as paper or plastic which is quite flexible, the sheet when doubled upon itself naturally bulges outwardly in the

2

shape of a flattened tube providing an unexpected degree of stiffness as contrasted with its bulk and weight.

Further objects of the invention have been to provide a cornice which may be fabricated inexpensively from sheet material and conveniently fitted and installed by the householder to eliminate the use of curtain rods for the support of the curtains or drapes and to provide a cornice structure which may be furnished to the householder in blank form, compactly packaged for convenience in storage and handling, which is conveniently assembled and fitted without the use of special skills or tools.

5 In practice, the improved cornice or valance is constructed in the form of a blank sheet, either printed or having a decorative covering. If desired, the decorative covering may be applied to both sides of the blank sheet, thus permitting the housewife to fold the blank with either pattern to the outside. In other instances, the decorative pattern may be printed on both sides or one side of the blank sheet may be printed with directions for erecting the cornice, in which case the decoration would be applied to one side only. The unit is designed to be packaged and sold in flat condition for which purpose the blank is scored transversely and folded-over crosswise a number of times for compactness. In its preferred form, the blank sheet is made somewhat oversize in length so that it may be trimmed to length with a scissors for individual fitting by the housewife. It is provided with longitudinal score lines so that after 10 unfolding the package, it falls readily into its beam formation for convenience in assembly. The blank further includes an adhesive strip so that it can be permanently sealed in folded condition. After sealing the ends are bent to provide the required length and the ends are then 15 trimmed to space the cornice properly from the window. After the cornice is installed, the drapes or curtains are attached at its rear surface so that the cornice overlies and supports the draperies and provides a decorative valance which complements or matches the pattern of the drapes. By virtue of its tubular cross-section, the assembled cornice is exceptionally 20 straight and rigid although formed from relatively light weight materials.

45 In order to avoid trimming the blank to length, the cornice structure may be made telescopic by providing a central section and a pair of end sections whereby the end sections establish a

reasonably close fit with the center section but may be adjusted telescopically to provide the desired length instead of requiring that the unit be trimmed to the required length. It is contemplated with reference to this structure to provide a different decorative pattern for the center section panel such as by the use of a contrasting color or pattern to enhance the decorative value of the cornice. By providing a fairly close fit between the interfitting sections, the strength of the telescopic cornice is sufficient for its purpose. This style of cornice is made up of blank sections, suitably scored and decorated in the manner disclosed with reference to the one piece structure. It is erected for use in the same manner and the three units making up the structure are considerably smaller and provide a more compact package than the one piece construction.

Further salient features and objects of the invention will be more fully disclosed in the specification with reference to the accompanying drawings showing a preferred embodiment of the invention.

In the drawings:

Figure 1 illustrates a window as viewed from the inside with the improved cornice installed in position to support the window drapes.

Figure 2 is a sectional view taken on line 2—2, Figure 1, illustrating the beam section of the cornice, together with the devices for attaching the drapes to the cornice.

Figure 3 is a longitudinal sectional view taken on line 3—3, Figure 1, further illustrating the cornice and its attachment to the window frame.

Figure 4 is an enlarged fragmentary sectional view of an end of the cornice, further detailing the beam structure and the manner of attaching the ends of the cornice to the window frame.

Figure 5 is a view illustrating the packaged blank from which the cornice is formed, as supplied to the householder.

Figure 6 is a sectional view taken on line 6—6, Figure 5, further illustrating the manner of packaging.

Figure 7 is a view of the cornice blank unfolded preparatory to over-folding to make up the tubular beam structure, illustrating the longitudinal score lines defining the width of the cornice and the transverse score lines along which the blank is folded for packaging.

Figure 8 is a view similar to Figure 7, showing the rear face of the cornice after the marginal edges have been overfolded and joined.

Figure 9 is an enlarged sectional view taken on line 9—9, Figure 8, further detailing the assembled cornice beam structure.

Figure 10 is a view similar to Figure 2, illustrating a modified arrangement which includes a panel inserted at the center, lengthwise of the cornice to control the amount of ballooning after assembly.

Figure 11 is an exploded view illustrating a telescopic form of cornice which may be adjusted over a considerable range to fit the window frame without being trimmed.

Figure 12 is a view similar to Figure 11 showing the telescopic cornice unit assembled and installed upon a window opening.

Figure 13 is a face view of the cornice of Figure 12 partially broken away to further illustrate its construction.

Figure 14 is an enlarged fragmentary view detailing the application of angle brackets which may be applied to either form of the cornice for

mounting the unit relative to a flush type window frame.

Referring generally to Figure 1, the cornice indicated generally at 15, is shown in its application to a standard window frame 16, secured by means of thumbtacks or brads 17 which are driven into the ends of the frame. The cornice includes end pieces 18—18 which are bent at right angles to the longitudinal beam section 28 to space the cornice the desired distance from the window frame. Although disclosed in connection with a conventional residence window frame, it will be apparent that the cornice may be installed in other types of windows. If the window frame is flush with the wall surface, the angle bracket 43, shown in Figure 14, may be tacked directly to the frame surface and the end pieces 18 slipped upon the brackets as shown.

The window drapes or curtains indicated at 21 in Figure 1, may be of any preferred material, although the structure has been designed primarily for use with paper drapes so that the cornice may be covered with a paper material matching the drapes in color and texture. The drapes preferably are suspended from the rear surface of the cornice so that the cornice forms a decorative valance overhanging and extending across the upper portion of the drapes. In the present disclosure, the drapes are supported by means of hooks 22 which engage the upper edge of the cornice. The lower ends of the hooks engage the opposite ends of hanger bars 23, the upper edges of the drapes being secured to the bars by hemming or other means. This arrangement provides a dependable and secure attachment for the drapes which is invisible to the observer.

The cornice 15 is constructed from a sheet of fairly heavy paper or plastic material which is doubled over upon itself longitudinally with its edges joined together at the rear side to provide a semi-elliptical or flattened tube. The blank, as indicated at 24 in Figure 7, is approximately three times the width of the finished product and is provided with a pair of longitudinal score lines 25—25 to facilitate folding and to form the proper width. These score lines are pressed into the blank by the manufacturer and define a central portion 26 and marginal portions 27 and 28.

As shown in Figure 7, the margin 28 includes an adhesive strip 30 which extends beyond the edge to provide an adhesive flap indicated at 31. In the use of paper blanks, the adhesive strip is coated with a film of glue which may be made tacky by the application of moisture. If desired, however, the strip may be of the self bonding type which requires no moisture. As applied to a plastic sheet the adhesive strip is coated with a material appropriate for bonding to that specific plastic. In assembling the cornice, the householder first folds the marginal edge 27 over upon the central panel 26. The flap 30 then is moistened and the marginal edge 28 is folded over upon margin 27 and the adhesive flap 31 pressed firmly upon the over-folded margin 27 to secure the two margins together. The assembled cornice naturally assumes the form illustrated in Figures 8 and 9 due to the tendency of the stock to assume its flat condition. Although the cornice is formed from relatively flexible sheet material, exceptional strength and rigidity are derived from the elliptical tube section in its assembled condition as shown in Figures 2 and 9.

In the preferred form, the blank cornice sheets are furnished in lengths somewhat in excess of

the standard window widths. After assembly, the end sections 13-18 are bent rearwardly in accordance with the width dimension of the window frame and the excess material is trimmed off to locate the cornice in spaced relationship with the window frame as illustrated in Figure 3. The tacks 17 then are applied to secure the cornice permanently in place. As shown in Figure 4, the ends of the longitudinal portion 29 are pinched together as at 32 when the end sections 13 are bent back. The side walls of the longitudinal beam section spring apart naturally and by reason of the fact that air is trapped in the tube when the ends are bent.

The decorative effect of the cornice is provided preferably by applying a sheet of drapery material 33 to one side of the blank, although in some instances the pattern is printed directly on the blank. This sheet may be creped or embossed in any desired fashion to match with or carry out the pattern of the drapes to provide the desired decorative appearance. The sheet 33 preferably is treated with a humectant to eliminate wrinkles and fold marks due to moisture absorption. As shown in Figures 5 and 8, this covering material does not extend for the full width of the blank 24, leaving the exposed marginal edges 34 and 35 for the application of the adhesive strip 30.

As shown in Figures 5, 6, and 7, the cornice unit is furnished to the purchaser in packaged form. For this purpose, the blank is provided with a series of transverse score lines 36 along which it is folded to make up the package illustrated in Figure 5. The score lines 36 are spaced apart such that panels of increasing length are defined from one end of the blank to the other. By this arrangement, a compact package may be formed by successively overlapping the panels starting at the end of the blank, to form a flattened roll as shown in Figure 6. This package has been found to provide maximum compactness and to open out naturally so that the householder may conveniently flatten out the blank and fold it longitudinally to assemble the cornice. The transverse score lines 36 disappear after the blank is assembled to its beam shape by reason of the curvature in cross-section of the cornice walls and do not detract noticeably from its strength. When the blank is folded over into its beam form, the decorative sheet is stretched tautly across the front of the cornice to remove wrinkles and to present a smooth surface. The substantial width section of the cornice, combined with its semi-elliptical cross-section resists deflection in either plane and results in a structure of exceptional strength and rigidity combined with minimum weight and bulk.

In the modified structure disclosed in Figure 10, a panel 37 is placed within the cornice at the time of assembly. This panel is located approximately at the center lengthwise of the cornice and is somewhat narrower than the cornice width so that the ballooning of the cornice is controlled. For example, the panel may be $\frac{1}{4}$ " narrower than the inside width of the cornice so that the opposite edges of the panel engage the opposite edges of the cornice tube when a predetermined semi-elliptical cross-section is developed. The panel 37 may fit loosely within the cornice or it may be anchored in position by an adhesive or the like if desired. Also the length of the panel is immaterial, and in some instances it may extend for the full length of the cornice.

It has further been contemplated to apply the

decorative covering 33 in the form of a tube which may be slipped upon the cornice after it is folded over and glued. The soft drapery paper is slightly under sized so that when it is slipped upon the cornice, it is under slight tension to dispel wrinkles or folds which may have been caused in packaging.

By reason of the longitudinal fold lines and the gummed strip 31, the valance is conveniently and quickly assembled by the householder. By reason of its decorative covering, the cornice completes the decorative effect of the draped window to carry the color scheme from one drape to the other. It serves also to hide all rods, fixtures, window shades and the like which are normally installed at the top of the window and provides a strong and dependable support for the drapes.

As disclosed in Figures 11 to 13 inclusive, the cornice unit may be in the form of a telescopic structure constituting a center section 40 and a pair of end sections 41-41 telescopically engaged within the center section. This structure is made up of blank sheets in the same manner as previously disclosed and provides the same tubular cross-section. However, the center section is slightly larger in inside diameter than the end sections 41-41 so that a sliding fit is established, permitting the end sections to be adjusted relative to the center section. By this arrangement the unit may be adjusted longitudinally to fit the window opening conveniently without trimming the ends. The blank sheets making up the sections 40 and 41 are constructed in the same manner as previously disclosed, including score lines 35 and adhesive strips to facilitate assembly. The blank sheets are decorated either by means of a decorative pattern printed directly on the blank sheets or by the use of a decorative covering adhesively secured to the sheets as above noted.

40 The decorative pattern of the center section 40 may differ from that of the end sections so as to provide a decorative scheme to enhance the attractiveness of the unit.

As shown in Figure 14, angle brackets 42 are provided for mounting the cornice unit relative to the window opening. These brackets are utilized in cases where the window frame is flush with the wall surface wherein the angular ends 18 of the units cannot be tacked directly to the window frame in the manner shown in Figure 4. The mounting brackets are utilized in conjunction with either the one piece cornice unit or with the telescopic unit and are furnished with the shade package in flat condition with a score line 55 to delineate the foot portion 43. The brackets 42 are attached to the window frame or wall by tacks 17 and the ends 18 of the cornice are slipped upon the bracket and held in place by frictional engagement.

60 In order to provide greater strength the angle brackets preferably are fabricated from a sheet of fibre or plastic material doubled upon itself to and seamed from a flattened tube as shown in Figure 14. However, the brackets may be of single thickness if appropriate sheet material is used.

Having described my invention, I claim:

70 1. A cornice for attachment to a window comprising; a beam formed of flexible sheet material having a pair of walls joined together along opposite longitudinal edges, said walls in cross section being ballooned outwardly in opposite directions to provide spacing between the walls of said beam longitudinally thereof to stiffen the same transversely of its load supporting axis, and

a panel disposed within said beam having a width dimension less than the beam to control the ballooning of said spaced walls.

2. A cornice for attachment to a window comprising a beam formed from a flat blank of relatively thin sheet material, the sheet material being flexible and having a bending resistance adapting the blank to spring normally to a flat condition upon being bent, said blank having a pair of spaced score lines extending longitudinally thereof delineating a central panel having substantial width extending longitudinally of the blank and a pair of integral co-extensive marginal panels along opposite sides of the central panel delineated by said score lines, said score lines being pressed into the blank and decreasing partially the bending resistance of the blank along said score lines, said marginal panels each having a width dimension which is substantially greater than one half the width dimension of the central panel, said marginal panels being folded over toward one another upon the central panel and having their outer marginal edges overlapped one upon another and joined together, said score lines by their partial bending resistance tending to spring said marginal panels and central panel outwardly with respect to one another thereby causing said central panel and marginal panels to bulge outwardly relative to one another to provide a beam having an elliptical cross section when said marginal edges are joined together.

3. A cornice for attachment to a window comprising a beam formed from a flat blank of relatively thin sheet material, the sheet material being flexible and having a bending resistance adapting the blank to spring normally to a flat condition upon being bent, said blank having a pair of spaced score lines extending longitudinally thereof delineating a central panel having substantial width extending longitudinally of the blank and a pair of integral co-extensive marginal panels along opposite sides of the central panel delineated by said score lines, said score lines being pressed into the blank and decreasing partially the bending resistance of the blank along said score lines, said marginal panels each having a width dimension which is substantially greater than one half the width dimension of the central panel, a covering sheet extending about the external surface of the beam, said covering sheet being formed of a pliable material which is thinner and more flexible than said blank material, said covering sheet being of substantially the same configuration as the blank and having its longitudinal edges secured to the free edges of said marginal panels when the blank is in flat condition, said marginal panels being folded over toward one another upon the central panel and having their outer marginal edges overlapped one upon another and joined together, the covering sheet being stretched tautly upon the external surface of the beam by the folding of the marginal panels upon the central panel, said score lines by their partial bending resistance tending to spring said marginal panels and central panel outwardly with respect to one another thereby causing said central panel and marginal panels to bulge outwardly relative to one another to provide a beam having an elliptical cross section when said marginal edges are joined together.

4. A packaged sheet blank adapted to form a cornice for attachment to a window and adapted to support draperies with respect to the window, said sheet blank comprising; an elongated

flat blank formed of relatively thin sheet material, the sheet material being flexible and having a bending resistance adapting the blank normally to spring to a flat condition, said sheet blank having a pair of spaced parallel score lines extending longitudinally thereof, said score lines being pressed into the sheet blank and decreasing partially the bending resistance of the blank along said score lines, said score lines being spaced to provide an elongated central panel having substantial width and an integral pair of marginal panels along opposite side edges of the central panel, said marginal panels collectively having a width dimension which is substantially greater than the width of the central panel, the marginal panels being foldable over toward one another upon the central panel with their marginal edges overlapped one upon another and joined together to form one wall of the cornice, said sheet blank having a series of transverse score lines spaced longitudinally of its length and extending for the full width thereof, said transverse score lines adapting the sheet blank to be rolled upon itself to form a compact flat package, said longitudinal score lines by their partial bending resistance tending to bulge said marginal panels and central panel outwardly with respect to one another when the marginal panels are overlapped upon the central panel and joined together, said outward bulging of the panels providing a beam which is elliptical in cross section having sufficient rigidity to support the draperies, said outward bulging imparting a curvature in cross section to the central panel and to the joined marginal panels, said curvature being effective to eliminate from the beam the effect of said transverse score lines.

5. A cornice for attachment to a window comprising a beam formed from a flat blank of relatively thin fibrous sheet material, the sheet material being flexible and having a bending resistance adapting the blank to spring normally to a flat condition upon being bent, said blank having a pair of spaced score lines extending longitudinally thereof delineating a central panel having substantial width extending longitudinally of the blank and a pair of integral co-extensive marginal panels along opposite sides of the central panel delineated by said score lines, said score lines being pressed into the blank and decreasing partially the bending resistance of the blank along said score lines, said marginal panels collectively having a width dimension which is greater than the width of the central panel, said marginal panels being folded toward one another upon the central panel and having their outer marginal edges overlapped one upon another and joined together, said score lines by their partial bending resistance tending to spring said marginal panels and central panel outwardly with respect to one another and thereby causing said central panel and marginal panels to bulge outwardly relative to one another to provide a beam having an elliptical cross section when said marginal edges are joined together, the opposite end portions of said beam being bent at right angles to provide end extensions, the outer ends of which are adapted to be fastened to a window for mounting the beam in spaced relationship to the window, the bulged walls of the beam being pinched together along the juncture lines of the angular end extensions, the bending resistance of the fibrous sheet material providing stiffness along said pinched lines joining the end extensions to the beam to maintain the beam longi-

tudinally in fixed position with respect to the window.
